PULLING ATTACHMENT FOR OIL-WELL DERRICKS.

1,162,392.

Specification of Letters Patent.

Patented Nov. 30, 1915.

Application filed December 24, 1914. Serial No. 878,876.

To all whom it may concern:

Be it known that we, CHARLES H. OVERLY and OWEN A. THOMPSON, citizens of the United States, residing at Independence, in the county of Montgomery and State of Kansas, have invented certain new and useful Improvements in Pulling Attachments for Oil-Well Derricks, of which the following is a specification.

10 This invention relates to pulling attachments for oil well derricks and is designed as an improvement in the pulling machines on which we secured United States Patents #1,110,003 and #1,110,004 on September 8, 15 1914, which machines are chiefly for use in connection with wells from which the derricks have been removed, though they may, with some trouble, be used on bobtailed derricks, it being understood that a bobtailed 20 derrick is one from which has been removed the engine, boiler, walking beam and bull-reel employed in the drilling of the well and the sinking of the tubing and rods therein.

Before the derrick is bobtailed, it is customary to pump it for a time through the 25 operation of the walking beam, and after being bobtailed it is pumped by means of a shackled rod line from a power house,—a large number of wells being thus pumped 30 from such power house. Ordinarily the bobtailed derricks of such wells are each equipped with a small pull reel, for the purpose of pulling the tubing and rods by means of horsepower, which rods are idle for the 35 greater part of their period of service because of the infrequency of the pulling operations. It will thus be evident that there is considerable expense attached to the equipment of a larger number of derricks with 40 such pull reels.

The appliances of our former patents, hereinbefore identified, are of great value for use with wells from which the derricks have been removed and can be used on bobtailed derricks lacking the small or special pull reels, but we have found that it is extremely desirable to not only produce a conveniently portable and easily set up pulling attachment for use on bobtailed derricks, 50 but one which can be used for either light or heavy service, that is, one which will combine the functions of the appliances of both patented structures.

Our object, therefore, is to produce a sin-

gle appliance of relatively small, light and compact construction, which can be used for light or heavy work, be easily and quickly transported from one derrick to another as needed, and easily and quickly set up or taken down and be controlled with absolute safety by a single operator.

With this general object in view, the invention consists in certain novel and peculiar features of construction and organization as hereinafter described and claimed, 65 and in order that it may be fully understood, reference is to be had to the accompanying drawings, in which:

Figure 1, is a side elevation of a bobtailed derrick equipped with a pulling attachment, 70 embodying our invention. Fig. 2, is an outer face view of the attachment. Fig. 3, is a section on the line III—III of Fig. 2. Fig. 4, is a similar section with certain parts differently positioned to show the operation 75 when light work is being performed. Fig. 5, is a similar view illustrative of the operation when heavy work is being done. Fig. 6, is a fragmentary perspective view to show the arrangement and relation of certain 80 of the parts of the attachment. Fig. 7, is a detailed perspective view of the controlling lever.

In the said drawings, 1 are parallel beams provided at their lower ends with notches 2 85 and at their upper ends with notches 3 for purposes hereinafter disclosed. Near their lower ends the beams are connected by parallel cross pieces 4 and near their upper ends by parallel cross pieces 5, the latter and one 90 of the cross pieces 4 being disposed at the outer edges of the beams 1. Extending transversely of the frame thus constituted and journaled in sliding boxes 6, mounted in brackets 7, secured on the outer edges of 95 the beams, is a shaft 8, and for convenience of portability carrying wheels 9 are mounted on the outer ends of said shaft, one of which wheels it is advisable to remove when the appliance is attached to a derrick, in the manner hereinafter explained. The attachment 100 travels upon the wheels 9 from one derrick to another and at such time is equipped with a tongue, not shown, as forming no part of the invention, and when about to be arranged in operative position, the machine is backed up close to the side of the derrick. 105 The tongue is then removed and the machine

is secured to the derrick in a manner hereinafter explained.

Journalized upon the shaft between the beams 1 is a reel, composed of a drum 10 to which one end of the pulling and lowering cable 11 is secured. At one side of drum 10 is a larger drum 12, the inner flange of which is provided with a notch 12^a. For performing very light work, such as raising a few sections of pumping rods, the cable 11 can be slipped through the notch 12^a so that it will wind upon the drum 12 which, being of greater diameter than drum 10, enables the light work to be performed more rapidly than it could be performed by winding the cable upon drum 10. At the opposite side of drum 10 is a large drum 13 to which one end of the ground line 13^a is secured, this line or cable being wound reversely on the reel, with respect to the cable 11, so that when the draft animals are driven forward they unwind ground line or cable 13^a for the purpose of winding cable 11 on drum 10. Reverse travel of the draft animals will permit the load of rods or tubing on the cable 11 to reverse the described operation of the drums.

Forming the outer sides or walls of drums 12 and 13 are brake wheels 14 for the reel, and arranged adjacent the peripheries of said wheels are brake bands 15, connected together by a tie bar 15^a, arranged between beams 1 so that the latter shall guard against disarrangement of the brake bands with respect to the brake wheels. The outer ends of the brake bands terminate in inturned lips 16 connected by angle bolts 17 to angle plates 18, secured to the cross piece 4 at the outer edges of the beams 1. The upper ends of the plates 18 are bolted as at 19 to the brake bands, and for purposes of adjustment, the said plates are provided with longitudinal slots 20, through which the bolting members extend. This connection between the brake bands and the anchoring plates 18 is to provide for adjustment or take up of the bands when the brake wheels 14 are appreciably reduced in diameter through wear. The opposite ends of the brake bands are connected pivotally as at 21 to a transverse crank shaft 22, the operative connection being made to a pair of similar cranks 23 of said shaft. The latter is journaled in bearings 24, secured to what may be termed the inner of the pair of cross pieces 4.

Journalized in a pair of bearing plates 25, secured to the outer cross piece 4 is a cranked rock shaft 26, and pivotally and slidingly engaging the cranked portion of the said rock shaft are the slotted lower ends of a pair of links 27 which extend upward through the lower portions of the brackets 7 and are pivotally attached to the lower ends of the bearing boxes 6, the slots or openings

in the lower ends of the brackets 7 being sufficiently large to permit the links to assume the angular positions indicated by dotted lines in Fig. 5, through the operation of the rock shaft 26, as hereinafter explained.

28 are helical springs mounted upon the links 27 and secured at their upper ends to said links and bearing at their lower ends upon washers 29 resting upon the rock shaft. By reference to Figs. 3 and 5 more particularly, it will be apparent that the pivotal point of connection between the rock shaft and the links 27 is slightly inward with respect to the plane occupied by the axes of said shaft and the reel, that is to say, said pivotal point of connection is off center, and to establish and maintain this relation of said parts as long as desirable, a retractile spring 30 connects the cranked portion of the shaft 26 with one of the beams 1. The spring is preferably secured to the beam by means of a hook 31 driven into the inner edge of the beam.

The operating lever 32 is arranged adjacent and preferably outward of one of the beams 1 and has a pivot portion 33, terminating in an inwardly projecting crank arm 34, said pivot portion 33 being journalized in bearing plates 35 secured to the outer cross piece 4 at the inner side thereof, and said crank arm 34 is pivotally connected by a link 36 with one of the cranks 23 of the shaft 22. It will thus be seen when the lever 32 is swung to the right in Fig. 3, it effects the application of the brake bands to the brake wheels as indicated in Fig. 5, and that continued movement of the lever to substantially the position which it occupies in Fig. 4 results, through the downward pressure imposed by the brake bands on the brake wheels, in moving the reel as a whole downward, the springs 28 being compressed in such operation, as indicated in Fig. 4, and it will be likewise obvious that relaxation of the power applied to lever 32 permits the compressed springs 28 to re-elevate the reel.

The construction as described is adapted for the performance of light work, and to adapt it to the performance of heavy work a bar 37 is pivoted to one of the cranks 23 and is provided in one edge with an elongated notch 38. When heavy work is to be performed this notched bar is swung from the inoperative position shown in Fig. 3 to the position shown in Fig. 5, which disposes its notched edge downward with the crank of shaft 26 engaging said notch. When the lever 32 is in normal position, as shown by Fig. 3, the outer wall of the notch is against the cranked portion of said shaft 26, and as the lever is operated it applies the brake bands to the brake wheels, as explained, and, at the same time, adjusts bar 37 until the rear wall of its notch is in engagement with

the cranked portion of shaft 26, as shown in Fig. 5, so that as the operative movement of the lever continues said bar shall break the off center connection between the 5 shaft 26 and the reel and cause said shaft to swing outwardly to the position indicated by dotted lines in Fig. 5, it being understood that as this occurs the reel is moved downward without compressing springs 28, 10 because the links 27 swing outward, as indicated by dotted lines in the last-named figure, to accommodate the downward movement of the reel.

As hereinbefore explained, the machine, 15 while still equipped with two wheels 9, is backed up close to the derrick 39 and after the tongue has been removed the wheeled frame is tilted downward at its rear end until the notched lower ends of the beams 20 are adjacent the flooring 40 of the derrick. A block and tackle connection is then made between a ring 41 on the upper part of the frame and the opposite side of the derrick, as indicated diagrammatically by cable 42 25 and tackle block 43, so that by hauling upon said cable and suitably guiding the frame, the notches 2 of the latter can be caused to engage the adjacent edge of the flooring and the frame tilted until its upper notches 3 receive the first girt of the adjacent side of the derrick. The frame is then secured in any suitable manner to the derrick and the elevating tackle for the cable 42 may be removed. This attachment is adaptable instantly to accommodate light or heavy loads and will perform the functions of both of the structures of our prior patents and has the merit of the latter as regards safety for and safety in operation by the operator as distinguished from the pulling machines employing wheel pegs, ratchet levers or kinking devices.

10 This device, in addition to the advantage of performing the functions of both of our prior structures is also of smaller and more compact and hence more conveniently portable construction. Furthermore, it can be 15 set up or taken down with greater ease and facility on bobtailed derricks.

From the above description it will be apparent that we have produced a pulling attachment for oil well derricks which embodies the features of advantage enumerated as desirable and while we have illustrated and described the preferred embodiment of the invention, it is to be understood that we reserve the right to make such changes 25 as properly fall within the spirit and scope of the appended claims.

We claim:—

1. A pulling attachment for oil well derricks, comprising a suitable frame, a winding mechanism thereon, a movable journal support for the winding mechanism, a rock shaft mounted on the support, a link connection between the rock shaft and said journal support, manually operable means 30 for depressing the journal support and winding mechanism, and yielding means for preventing the accidental operation of said rock shaft when the winding mechanism is depressed.

40 2. A pulling attachment for oil well derricks, comprising a suitable frame, a winding mechanism thereon, a movable journal support for the winding mechanism, a rock shaft mounted on the support, a link connection between the rock shaft and said journal support, braking appliances for the winding mechanism, manually operable means for operating the braking appliances to prevent rotation of the winding mechanism and then causing said appliances to effect depression of the winding mechanism, and yielding means for preventing accidental operation of said rock shaft until the braking operation has been performed.

55 3. A pulling attachment for oil well derricks, comprising a suitable frame, a rock shaft mounted thereon, and provided with an upwardly projecting crank, journal boxes above and pivotally linked to the crank of 60 the rock shaft and adapted for up and down movement on the frame, the links having endwise slidable movement with respect to the crank shaft, springs mounted on the links and supported by the crank of the 65 rock shaft and exerting upward pressure

on the links to hold the journal boxes normally elevated, a winding mechanism journaled in said boxes, and a manually operable means for depressing the journal boxes against the resistance of said springs.

4. A pulling attachment for oil well derricks, composing a suitable frame, a rock shaft mounted thereon, and provided with an upwardly projecting crank, journal boxes above and pivotally linked to the crank of 70 the rock shaft and adapted for up and down movement on the frame, the links having endwise slidable movement with respect to the crank shaft, springs mounted on the links and supported by the crank of the rock shaft and exerting upward pressure on the links to hold the journal boxes normally elevated, a winding mechanism journaled in said boxes, yielding means for holding the crank of said shaft off center with respect to 75 the plane occupied by the axis of said shaft and of the journal boxes, and manually operable means for depressing the journal boxes against the resistance of said springs.

80 5. A pulling attachment for oil well derricks, comprising a suitable frame, a rock shaft mounted thereon, and provided with an upwardly projecting crank, journal boxes above and pivotally linked to the crank of 85 the rock shaft and adapted for up and down movement on the frame, the links having endwise slidable movement with respect to the crank shaft, springs mounted on the links and supported by the crank of the rock shaft and exerting upward pressure 90 on the links to hold the journal boxes normally elevated, a winding mechanism journaled in said boxes, and a manually operable means for depressing the journal boxes against the resistance of said springs, in 95 combination with means adapted for actuation by said manually operable means to operate said crank shaft and thereby leave the winding mechanism and said journal boxes free to move or to be moved downwardly.

100 6. A pulling attachment for oil well derricks, comprising a suitable frame, a rock shaft mounted thereon, and provided with an upwardly projecting crank, journal boxes above and pivotally linked to the crank of 115 the rock shaft and adapted for up and down movement on the frame, the links having endwise slidable movement with respect to the crank shaft, springs mounted on the links and supported by the crank of the 120 rock shaft and exerting upward pressure on the links to hold the journal boxes normally elevated, a winding mechanism journaled in said boxes, and a manually operable means for depressing the journal boxes 125 against the resistance of said springs, in combination with means adapted for actuation by said manually operable means to operate said crank shaft and thereby leave the winding mechanism and said journal 130

boxes free to move or to be moved downwardly, and braking appliances for the winding mechanism connected to said manually operable means to be actuated to lock 5 the winding mechanism against rotation prior to the operation of the crank shaft.

7. A pulling attachment for oil well derricks, comprising a suitable frame, a rock shaft mounted thereon provided with an 10 upwardly projecting crank, journal boxes mounted on the frame for up and down movement, links pivoted to the journal boxes and provided with longitudinal slots receiving the crank of the rock shaft, a winding 15 mechanism journaled in said boxes, and brake wheels forming a part of the winding mechanism, springs mounted on the links and resting on the crank of said shaft and engaging the links to hold the journal 20 boxes normally elevated, brake bands adjacent the brake wheels and anchored at one end to said frame, a shaft provided with cranks pivotally connected to the opposite 25 ends of said bands, a manually operable lever mounted on the frame and provided with a crank arm, a link pivotally connecting said arm to operate said crank shaft when said lever is operated to operate the 30 braking mechanism, a bar pivotally mounted on the crank shaft and provided with a notch in its under side receiving the crank of said rock shaft and adapted under the operation of said lever to slide inoperatively 35 on the crank shaft and then under the continued operation of said lever to impart rotation to the rock shaft to permit the brake bands to pull the winding mechanism downward.

8. A pulling attachment for oil well derricks, comprising a suitable frame, a rock 40

shaft mounted thereon provided with an upwardly projecting crank, journal boxes mounted on the frame for up and down movement, links pivoted to the journal boxes and provided with longitudinal slots 45 receiving the crank of the rock shaft, a winding mechanism journaled in said boxes, and brake wheels forming a part of the winding mechanism, springs mounted on the links and resting on the crank of said shaft 50 and engaging the links to hold the journal boxes normally elevated, brake bands adjacent the brake wheels and anchored at one end to said frame, a shaft provided with cranks pivotally connected to the opposite 55 ends of said bands, a manually operable lever mounted on the frame and provided with a crank arm, a link pivotally connecting said arm to operate said crank shaft when said lever is operated to operate the 60 braking mechanism, a bar pivotally mounted on the crank shaft and provided with a notch in its under side receiving the crank of the said rock shaft and adapted under the operation of said lever to slide inoperatively 65 on the crank shaft and then under the continued operation of said lever to impart rotation to the rock shaft to permit the brake bands to pull the winding mechanism downward, and a retractile spring for 70 resisting the rotation of the shaft by said notched bar.

In testimony whereof we affix our signatures, in the presence of two witnesses.
